(57) **CLAIM**

The ornamental design for a multiple light bulb socket adapter, as shown and described.

DESCRIPTION

FIG. 1 is a first perspective view of a multiple light bulb socket adapter.

FIG. 2 is a second perspective view of the multiple light bulb socket adapter.

FIG. 3 is a first side view of the multiple light bulb socket adapter.

FIG. 4 is a second side view of the multiple light bulb socket adapter.

FIG. 5 is a third side view of the multiple light bulb socket adapter.

FIG. 6 is a bottom view of the multiple light bulb socket adapter; and,

FIG. 7 is a top view of the multiple light bulb socket adapter. The male screw base shown at the bottom of FIGS. 1-6 is shown in broken lines and forms no part of the claimed design.

1 Claim, 6 Drawing Sheets
